JACQUES BOGOPOLSKY, OF GENEVA, SWITZERLAND, ASSIGNOR TO SOCIETE ANONYME
POUR L'EXPLOITATION D'INVENTIONS "I. S. A.", OF GENEVA, SWITZERLAND.

AUTOMATIC SHUTTER-STARTING DEVICE FOR PHOTOGRAPHIC CAMERAS.

1,408,976.

Specification of Letters Patent.

Patented Mar. 7, 1922.

Application filed March 17, 1920. Serial No. 366,522.

To all whom it may concern:

Be it known that I, JACQUES BOGOPOLSKY, citizen of the Republic of Ukraine, residing at Geneva, Canton of Geneva, in the Federation of Switzerland, have invented certain new and useful Improvements in Automatic Shutter-Starting Devices for Photographic Cameras, of which the following is a specification.

10 The invention relates to automatic starting devices for shutters of photographic cameras of any construction whatever, and it is intended to provide a reliable means for having the said shutter successively and automatically opened and closed at a predetermined time and for a predetermined length of exposure.

15 The invention consists substantially in the combination of a main spring acting upon an axis, the rotation of which is controlled by any well-known regulator whatever so as to turn at a constant speed, the said axis being fitted with suitably adjustable devices (cams or the like), intended to successively act upon two levers, one of which causes the opening of the shutter and the other one the closing of the same.

20 The accompanying drawing shows different constructions illustrating the invention. Each of the Figures 1 to 3 shows diagrammatically one construction of the mechanism.

25 The Figures 4 and 5 show details of the construction shown in Figure 3.

30 In the construction shown in Figure 1, *a* is a spring barrel, the speed of which is controlled by the wheels *h*, acting upon a speed regulator consisting of a fly wheel.

35 The axis of the spring barrel *a* carries a fixed cam *b* and an adjustable disk *d* and a cam *b*¹, which is adjustable with regard to the cam *b*.

40 In front of the said two cams *b* and *b*¹, two starting levers *c* and *c*¹ are provided. The lever *c* has a projection *f* which engages a lever *i* and tends to maintain the same in its depressed position shown in full lines in

45 Fig. 1. The said lever *i* acts upon one end of a spiral spring *r*, the other end of which bears upon the bottom of a cylindrical slide *s* moving in a fixed cylindrical guide *t*. The bottom of the cylinder *s* is supported by a projection *f*¹ of the lever *c*¹ acted upon by the cam *b*¹, and a spiral spring *r*¹, which is weaker than the spring *r* which tends to force

50 the said cylinder *s* downward when the pro-

jection *f*¹ is retracted by the action of the cam *b*¹.

55 The lever *i* acts upon the piston *t*¹ of a Bowden *w*, connected by means of a flexible cable to the shutter.

60 A spring *o* causes the levers *c* and *c*¹ to return to their starting position shown in Fig. 1, whenever they have been acted upon by their respective cams *b* and *b*¹.

65 By suitably regulating the angular position of the cam *b*¹ with regard to the cam *b*, it is possible to fix the time which elapses between their respective action.

70 When the device has actuated the shutter, the lever *i* is placed in the position shown by dotted lines in Fig. 1, and hence it may be brought again to its initial position shown in full lines by any suitable means whatever, (not shown) causing the slide *s* to be depressed and the spiral spring *r* to be compressed as shown until the bottom of the slide *s* is engaged by the projection *f*¹ of the lever *c*¹. The spring is then wound up and the barrel set in such an angular position that it will have to turn one complete revolution before the cam *b* engages the lever *c* and opens the shutter.

75 The gear wheels are provided with a stopping device, which may be released whenever it is desired to start the apparatus.

80 This allows the operator to do such releasing after he has set his camera into position, and he may then effect the release and go to a point where he himself will be included and taken in the picture when the automatic device opens the shutter.

85 In the construction shown by Fig. 2 there is again a spring barrel *a* and speed controlling gears *h*. The axis of the spring barrel also carries a fixed cam *b* and an adjustable disc *d* with a cam *b*¹, in the paths of which are provided two levers *c* and *c*¹, having suitable projections *f* and *f*¹ respectively.

90 The projection *f* engages a lever *j* intended to act upon the Bowden *w*, as shown, and the spiral spring *r* connects the said lever *j* to a lever *n* which is provided with a spiral spring *r*¹, weaker than the spring *r*, the other end of which is secured to a fixed point of the casing.

95 To use this device it is first necessary to raise the lever *m* to its upper position as shown in the drawing when the projection *f*¹ of the lever *c*¹ engages in the corresponding recess of said lever *m*, whereby the

110

2
spring r is suitably extended, the lever i being held in its depressed position by the projection f of the lever c . Whenever the cam b acts upon this lever c , the spring r pulls 5 the arm k of the lever i from the full line position to that indicated by dotted lines at k^1 , and the Bowden w is acted upon, as shown in the drawing. When the cam b acts in turn upon the lever c^1 , the projection f^1 is re- 10 tracted and both levers j and n are thrown back to their starting position.

In the construction shown in Figs. 3 to 5 there is again provided a spring barrel a with a fixed cam b and an adjustable cam b^1 . 15 The train of gears controlling the speed of rotation of the barrel a is not shown as it may be of the same construction as hereinbefore described. There is a piston U , carrying a head-piece i^5 , and sliding in a bearing V , connected by means of a spiral spring r , to the starting lever m . A spiral spring r^1 is placed between the head piece i^5 and the bearing V .

The lever m has a tooth or projection n , 25 which engages a projection f^1 of the lever c^1 acted upon by a spring c^2 , and the lever c is provided with a tooth or projection f intended to engage the head piece i^5 , as shown in dotted lines in Fig. 6.

30 Fig. 5 shows the construction of the spring barrel axis a of Fig. 4. b is the fixed cam and d^1 is an adjustable disc which is pressed by a spiral spring s against the disc d , fixed to the barrel a . The said adjustable disc d^1 35 carries the cam b^1 ; therefore the angular position of the cam b^1 with regard to the cam b is obtained by suitably setting the adjustable disc d^1 on the barrel a .

The operation of this construction is as 40 follows:

The operator lifts the lever m , thereby expanding the spring r until the tooth n engages the projection f^1 of the lever c^1 . This causes the head i to engage the projection f of the lever c and to hold back the bearing V to which the spring r is attached. 45

When the cam b acts upon the lever c , the projection f is withdrawn and the head i of the piston U is released and its head i^5 50 strikes the piston t of the bowden, causing the shutter to be opened.

As soon as the cam b^1 strikes the spring c^2 of the lever c^1 , the projection f^1 is withdrawn and the lever m released so that both 55 lever m and piston U are thrown back into their lower position when the shutter is being closed again.

I claim as my invention:

1. An apparatus for operating shutters for 60 photographic cameras comprising a shaft, means for turning the same at a constant speed, means for opening and closing the shutter, arms for actuating the means for opening and closing the shutter, tension devices associated with the said arms, levers

for normally maintaining the said arms in initial positions, and adjustable devices on the said shaft for tripping the said arms for successively actuating the devices for opening and closing the shutter to first open and 70 then close the same.

2. An apparatus for operating shutters for photographic cameras comprising a shaft, means for turning the same at a constant speed, means for opening and closing the 75 shutter, arms for actuating the means for opening and closing the shutter, a tension device connecting the said arms so that when both are released they move together, levers for normally maintaining said arms in initial 80 positions, adjustable devices on the said shaft for successively tripping said arms to first release one arm, permitting the same to be actuated by the tension device to actuate the means for opening and closing the shutter to 85 open the same and then for tripping the other arm to release both the said arms, and tension devices for then actuating both the said arms to return one of the same to its initial position. 90

3. An apparatus for operating shutters for photographic cameras comprising a shaft, means for turning the same at a constant speed, means for opening and closing the 95 shutter, pivotally mounted arms for actuating the means for opening and closing the shutter, a spring connecting the free ends of the said arm, pivotally mounted levers for normally maintaining the said arms in initial positions, adjustable devices on the said 100 shaft, one of which is adapted to engage one of the said levers to release one of the said arms permitting the actuation of the same by the said tension device to operate the means for opening and closing the shutter to open 105 the same and the other adjustable device to engage the other arm to release the other lever to permit the operation of the means for opening and closing the shutter to close the same, and a spring for moving the second arm for actuating the means for opening and closing the shutter to close the same and simultaneously to return the first arm to its initial position. 110

4. An apparatus for operating shutters 115 for photographic cameras comprising a shaft, means for turning the same at a constant speed, means for opening and closing the shutter, an arm, a lever, an adjustable device on the said shaft for engaging the lever 120 to release the said arm, a tension device for actuating the arm when thus released to operate the means for opening and closing the shutter to open the same, a second arm, a second lever, a second adjustable device on 125 the said shaft for engaging the second lever to release the second arm, and a tension device for actuating the said second arm when thus released to operate the means for opening and closing the shutter to close the same. 130

5. An apparatus for operating shutters for photographic cameras comprising a shaft, means for turning the said shaft at a constant speed, means for opening and closing the shutter, an arm, a lever, a device adjustably mounted on the shaft for engaging the lever to release the said arm, a second arm, a second lever, a second device adjustably mounted on the said shaft, a spring connecting the said arms whereby when the first aforesaid arm is released the same is actuated to operate the means for opening and closing the shutter to open the same, and a tension device for simultaneously actuating both said arms when the said second arm is released for actuating the means for opening and closing the shutter to close the same.

10 6. An apparatus for operating shutters for photographic cameras comprising a shaft, means for turning the said shaft at a constant speed, a Bowden device for opening and closing the shutter, an arm, a lever, a cam revolvably adjustable on the said shaft

15 for engaging the said lever to release the said arm, a second arm, a second lever, a second cam revolvably adjusted on the said shaft for engaging said second lever to release the said second arm, a spring connecting the free ends of the said arms whereby when the first aforesaid arm is released the same is actuated to operate the said Bowden device to open the shutter, and a tension device for simultaneously actuating both the said arms when the said second arm is released by the said second adjustable cam for simultaneously actuating the said levers to cause the said second arm to engage the Bowden device to actuate the same for closing the said shutter.

In testimony whereof I affix my signature 40 in presence of two witnesses.

JACQUES BOGOPOLSKY.
